SHEET METAL BENDING TOOL

Theron F. Pauls, Godfrey, III., assignor to Olin Mathieson Chemical Corporation, a corporation of Virginia

Original application June 11, 1954, Serial No. 436,021, now Patent No. 2,835,025, dated May 20, 1958. Divided and this application Dec. 16, 1957, Ser. No. 706,534

1 Claim. (Cl. 81—15)

This invention relates to the manufacture of sheet metal articles and more particularly to the manufacture of hollow articles from sheet metal by fluid pressure inflation.

Therefore, it is an object of this invention to provide an apparatus for forming an inlet opening at the edge of the hollow sheet.

The invention will be better understood in connection with a description of a specific embodiment together with an accompanying drawing in which:

Figure 1 is a side elevational view partially in cross section showing the angular relationship of the shears and the metal plate for adapting the plate for opening by one embodiment of the tool of this invention;

Figure 2 is a side elevational view also partly in cross section showing a succeeding stage of the cutting operation;

Figure 3 is a fragmentary perspective view showing the structure of the cut produced by the shears;

Figure 4 is an elevational view showing one tool suitable for operating on the edge structure to accomplish opening, with the metal plate shown in the cross section at the opening; and

Figure 5 is a perspective view of another embodiment of the opening tool of this invention.

For purposes of illustration, the tool of this invention will be described by reference to its application to forming an opening in an internally laminated sheet obtained by the method described in U.S. Patent No. 2,690,002. As illustrated in the drawings, an embryonic system of passageways, within the metal sheet, is provided by a connecting laminar portion extending from the system of passageways to an edge of the sheet. In order to facilitate this sheet for expansion, the edge, to which the connecting laminar portion extends, is cut or sheared to provide a beveled edge on which the tool of this invention may operate.

More specifically by reference to Figures 1, 2 and 3 of the drawing, such a sheet metal plate 1 of annealed aluminum having an included laminar pattern of internally disposed system of embryonic passages or internal laminations is provided with a beveled edge by being positioned between open shear blades 3 and 4 so that an extension 2 of the pattern is disposed at the bight of the shear. It is advantageous to select in some cases a sheet metal plate 1 having a dual pattern the extension 2 of each of which is common to both. It is apparent that with such an arrangement cutting of sheet metal plate 1 at the extension 2 at the axis of pattern symmetry provides two units with only one cut 15 each of which will be suitable for further operation in accordance with this invention which will become apparent hereinafter.

The front faces 5 and 6 of shear blades 3 and 4 respectively are out of line sufficiently to provide the usual clearance necessary for satisfactory operation of the shearing mechanism. Leading face 7 of blade 3 is swept back as shown in Figures 1 and 2 so that the cutting edge of leading face 7 passes and crosses the cutting edge of

2

leading face 8 of blade 4 with obliquity at the usual angle, generally about 5°. The sheet metal plate 1 is disposed in the bight of the shear in such a manner that the plate makes an angle with the cutting plane of the shear to provide a beveled edge such as illustrated in Figure 3.

The beveled sheet metal edge structure specifically shown in Figure 3 is obtained in accordance with the teachings of the parent co-pending application Serial No. 436,021 filed June 11, 1954, now U.S. Patent No. 2,835,025. This beveled edge is characterized by a sloping edge which as a general rule is made up of the smoothly sheared or burnished portion 14 and the fractured portion 18 across both of which the front face 5 of shear blade 3 passed. Indentation 16 is merely the mark left by the leading face 8 of the other shear blade 4. At about the line of demarcation between portions 14 and 18 of the sloping cut a line 17 of the inlet extension 12 is very ostensibly exposed. This line 17 is thus not only very readily located with the unaided eye but is adaptable for application by the opening device of this invention with no difficulty.

As can be readily seen in Figure 3, line 17 defines a potential opening to the embryonic system of passageways between the metal sheet and is defined by a protuberant lip portion 21 formed from the protruding metal sheet component at the beveled edge and by the receding lip portion 22 formed from the receding component sheet at the beveled edge to adapt the sheet to operation by the tool of this invention.

In order to accomplish opening of the inlet extension 12 at the line of exposure 17, an opener such as shown in Figure 4 may be applied to produce the opening 20. The tool consists of a body portion 23 having a stepped portion or shoulder 24 spaced from a bearing surface 25 by a gap 26 the width of which is equal to one-half the thickness of sheet metal unit 10. For example, the width of gap 26 is about 0.031 of an inch when the gage of unit 10 is 0.062 of an inch. Tool body 23 is provided with the pivot point 27 about which body 23 together with its shoulder 24 may be turned so that shoulder 24 bears against the protuberant lip 21 thereby prying lip 21 away from receding lip 22 to form the opening 20.

Tool body 23 of the opener also carries means for forming an entrance at inlet extension 12. The means shown takes the form of a drift punch 28 the front end of which is pointed at 29 to facilitate entry of the punch into the initial opening 20.

Figure 5 illustrates the above opening tool as a separate hand operated device which comprises a tool holder 31, such as a rigid rod and the like, having mounted on its rear portion a dimensional transition member 32. This transition member 32 may be of any convenient configuration, such as the conical form illustrated, to provide a gradual transition from the holder 31 to the handle or grip 35 mounted on the rear end of member 32. Handle 35 is preferably, as illustrated, knurled at portions 34 to provide an additional gripping aid when the tool is hand operated.

Mounted on the front end of rod 31 is an opener 23 reciprocating the protuberant lip 21 from the receding lip 22 of the sheet unit 10. As above, the opening tool has a stepped or shoulder portion 24 spaced from a bearing surface 25 by a slot or gap 26. The dimension of slot 26 is substantially equal to the difference between the thickness of the sheet metal unit and the thickness of the receding lip 22. This dimension enables the slot to receive therein the protuberant lip 21 and to thereby enable the edge of the shoulder portion 24 to be engaged thereon below the exposed line 17 of the extension 2.

Separation of the lips, at the bevel, is accomplished by applying a force on the protuberant lip 21 through the

edge of the shoulder portion 24 upon pivoting it about a fulcrum resulting from the action of the edge 27, of bearing surface 25, against the sheet metal unit at a point, inwardly of the beveled edge. Upon pivoting or rotating the tool about the extended edges 27, bearing against the sheet metal unit, the shoulder portion 25 bends the protuberant lip 21, by the applied force thereon, to pry it away from the receding lip 22.

Since many other embodiments of this invention may occur to those skilled in the art, it is to be understood the foregoing is intended by way of illustration of a preferred embodiment and not as a limitation of the scope of the present invention except as set forth in the appended claim.

This application is a division of co-pending application Serial No. 436,021 filed June 11, 1954, now U.S. Patent No. 2,835,025.

What I claim as my invention is:

A hand tool for effecting an opening between a pair of superposed metal sheets, having sealed together edge portions, and forming a sheet metal unit; said unit having beveled edges at one end thereof and a slit opening into the interior thereof through the beveled end portion; one of the metal sheets protruding beyond the other sheet at

the beveled end of the unit; said hand tool comprising a tool body provided with a slot for the reception of the lip portion of the protruding metal sheet and with a fulcrum projection in extension of the bottom of the slot, said slot defining a gap of a dimension substantially equal to the difference between the thickness of the sheet metal unit and the thickness of the other of said sheets; said fulcrum projection constituting pivot means on one side of the gap; the forward edge of the upper wall of said slot constituting a bending means for engaging the protruding lip portion; said forward edge having a width not in excess of the width of said sheet, for applying a force to the sheet about said fulcrum, in a direction away from the other sheet and substantially normal to the plane of the sheet unit, and handle means for manipulating the tool body.
